UNITED STATES PATENT OFFICE

2,538,450

ENGINE MUFFLER

Colon L. Gardner, Concord, N. C.

Application February 16, 1948, Serial No. 8,648

1 Claim. (Cl. 183—23)

1 This invention relates generally to mufflers for internal combustion engines, and more particularly to a muffler in which the exhaust gases are forced to travel through water prior to an escape thereof into the atmosphere.

It is a primary object of this invention to provide a muffler in which the highly heated exhaust gases, often carrying burning or incandescent particles of carbon, are made to travel through a water reservoir, thus quenching the burning particles and making the internal combustion engine safe for operation adjacent extremely dry and inflammable materials.

Another object of this invention, ancillary to the preceding object, is to provide a muffler which may be used to make automotive vehicles safe for operation in coal mines and other places where inflammable gases are likely to be encountered, in barns and graineries and other buildings where dust-laden air provides a hazard inasmuch as this dust-laden air often becomes ignited and explodes with terrific force, and in other localities where excessively hot gases or gases containing burning carbon would be dangerous.

Another object of this invention is to provide a muffler for internal combustion engines which will reduce the content of obnoxious gases ordinarily existing in the exhaust from internal combustion engines.

Still another object of this invention is to provide a muffler which will reduce the noise incident in the operation of an internal combustion engine to the greatest extent possible compatible with efficient operation of the engine, that is, to reduce the noise of operation without causing undue back pressure on the cylinders of the engine.

It is a still further object of this invention to employ the surrounding atmospheric air for cooling the water, as well as for cooling the gases immediately above the water reservoir, this air cooling being accomplished by provision of a plurality of pipes leading through the muffler casing.

Still another object of this invention is to provide improved baffle means in which each baffle is formed into a plurality of relatively inclined portions, the lowermost portions, that is, the portions immediately above the water reservoir, being inclined at a greater angle to the vertical than are the portions above these lowermost portions.

Yet another object of this invention is to provide a muffler with a complement of parts including a water gauge to show the level of the water in the reservoir, a float valve assembly to control this level, means facilitating the application of chemicals for suitably chemically burdening the

water in the reservoir, and finally for making the muffler very easily cleaned, the last feature being accomplished by making the top of the muffler removable and by providing a clean-out plug in the floor of the muffler.

Still another object is to provide a pitched or ridged roof for the muffler and to incorporate with this pitched roof an improved water trap construction, this water trap cooperating with the air cooling pipes and the novel baffle construction to make this muffler highly efficient and economical in its use of water.

And a last object to be mentioned specifically is to provide a muffler construction which is relatively inexpensive and practicable to manufacture, which is extremely safe, simple and convenient to use, to maintain and to clean, and which will give generally efficient and durable service.

With these objects definitely in view, this invention resides in certain novel features of construction, combination and arrangement of elements and portions as will be hereinafter described in the specification, particularly pointed out in the appended claim, and illustrated in the accompanying drawings which form a material part of this application, and in which:

Figure 1 is a vertical sectional view of the assembled muffler with the float valve assembly used to control the level of the water in the reservoir, portions of the muffler casing and valve assembly casing being shown in elevation, to facilitate the illustration of the float valve construction and to indicate how the air cooling pipes are terminally welded to the sides of the casing of the muffler;

Figure 2 is a top plan view of the structure illustrated in Figure 1, a portion of the pitched roof of the muffler being broken away to illustrate the construction of the baffle plates as viewed in plan;

Figure 3 is a top plan view of the float valve assembly, with the top plate thereof removed;

Figure 4 is a three dimensional view of one of the brackets used to support the valve assembly on the side of the muffler casing; and

Figure 5 is a horizontal sectional view of an upper portion of the muffler, the view being taken on a plane substantially on the line 5—5 in Figure 1.

Similar characters of reference designate similar or identical elements and portions throughout the specification and throughout the several views of the drawings.

Referring now to the drawings in detail, the environment wherewith this invention is adapted to be used will include an internal combustion

engine having an exhaust pipe securable to an inlet 10, and a source of cold water connected to the inlet pipe 12 in the float valve assembly generally indicated by the numeral 14.

This invention envisages inclusion of a muffler casing 16 which is represented in the drawings as substantially square in cross section, although this peculiar shape is not necessarily adhered to and this invention may be adapted for use with cylindrical and otherwise shaped casings. The casing 16 is provided with a sloping floor 18 having a clean-out plug 20 at the lowest point thereof, and the upper end of the casing is closed by a pitched or ridged roof 22 removably secured to the casing, as indicated by the bolts 24 so as to facilitate the cleaning of the muffler.

A single long baffle 26 extends from the upper end of the casing downwardly to within a short distance from the floor 18, this baffle 26 being bent into a plurality of angularly disposed portions and this baffle is positioned adjacent the inlet 10 so as to direct exhaust gases entering the casing 16 downwardly into the base portion of the casing which in operation will be filled with water and which will be referred to herein as the water reservoir 28.

A plurality of substantially similar baffle plates 30 and 32 are arranged in substantially parallel relationship within the upper portion of the casing 16 and adjacent pairs of said baffles 30 and 32 are connected by top wall structure 34 and the vertical edges of each of the baffles 30 and 32 are welded to the adjacent vertical side walls of the casing 16. Since the top wall structure 34 closes the space between integral pairs of baffles 30 and 32, access of gases from the water reservoir upwardly through the casing is restricted to the tubes 36 between adjacent baffles 30 and 32 which are not connected by wall structure 34. It should be carefully noted that each of these baffles is comprised of a plurality of portions which are bent in zig-zag fashion, with the lowermost portions of the baffles 30 being inclined at greater angles to the vertical than are the lowermost portions of the baffles 32, thus giving a slightly altered baffle action immediately above the water reservoir 28.

A plurality of air cooling pipes 38 are terminally welded to the vertical sides of the casing 16 as indicated at 40, these air cooling pipes being disposed above the reservoir 28, and these pipes are cooled by atmospheric air entering from the sides of the casing. A similar construction, involving the use of a plurality of air cooling pipes 42 is used to cool the water in the water reservoir 28. It will be noted that in each case the pipes 38 and 42 are welded internally of the casing 16, and heat is, of course, transferred from the gases above the water reservoir 28 and from the water in the reservoir 28, through the pipes 38 and 42 to atmospheric air within these pipes.

A pipe 44 is connected by a nipple 46 and the roof 22 so as to facilitate introduction of solvent or other chemicals wherewith the water in the reservoir 28 may be burdened to facilitate the cleaning of the muffler, the absorption of certain gases and for other purposes.

A water trap generally indicated by the numeral 48 is incorporated with the lower end of a gas exhaust outlet tube 50, this tube extending to the top of the roof 22. The lower end of the tube 50 has an out-turned substantially horizontal flange 52 which is apertured as at 54 75

and which carries an inverted pyramidal basin 56. The upper edges of this inverted basin 56 extend close to the roof 22 and above the level of the flange 52, while the lower end of the basin is apertured as at 58. It will be seen that an effective water trap is thus provided for trapping water carried upwardly by the exhaust gases to the roof 22, and it will be clear that water condensing out of these gases will trickle through the aperture 58 and return to the water reservoir through one or other of the tubes 36.

A sight gauge 60 is incorporated with the wall of the casing 16 to indicate the level of water in the water reservoir, and the float valve assembly 14 is connected to this water reservoir by a tube 62, while the casing 64 for the float 66 is mounted on the casing 16 by means of substantially U-shaped brackets 68 which may be welded to the casing 64 and bolted as at 70 to the casing 16. The float chamber or casing 64 communicates with a valve 70 through an aperture 72 in a top wall 74 of the float chamber or casing, and a rocker arm 76 is used to link the float 66 operatively with the valve 70, this rocker arm 76 being pivoted on the top wall 74, and a spring 78 is used to urge the valve 70 into open position when the float 76 falls as a result of the water reaching too low a level in the reservoir 28. The valve chamber 80 may be of conventional character and will, of course, communicate with the inlet pipe 12, while a top plate 82 for the valve assembly will be provided so as to make the various parts of the valve assembly of easy access.

The operation of this invention will be clearly understood from the foregoing description of the mechanical details thereof, taken in connection with the drawings and with the recitation of objects sought to be achieved by this invention. It is believed that all the objects recited are amply achieved by this invention and that exhaust gases after being processed by the muffler will escape through the exhaust outlet tube 50 completely quenched of all burning particles and relieved of a large proportion of the noxious gases contained therein.

Minor variations may be made in the exact construction and proportionment of the various elements of this invention without departure from the spirit and scope thereof and the scope of this invention should be determined only in accordance with a proper interpretation of the terminology used in the subjoined claim.

Having described the invention, what is claimed as new is:

A muffler for connection to an engine exhaust, comprising a casing having an inlet connected to said exhaust, a water reservoir in the bottom of said casing, a baffle directing exhaust gases from said inlet into said reservoir, a plurality of baffles mounted in said casing above said reservoir, a pitched roof on said casing, and a gas outlet tube through the highest part of said roof, said outlet tube extending into said casing and having a water trap on the lower end thereof comprising a substantially horizontal out-turned flange on the outlet tube, apertures in said flange, and an inverted pyramidal basin secured to the periphery of said flange and having its upper edges adjacent said roof and being apertured centrally.

COLON L. GARDNER.
